COAL STOKER

Walter M. Cross, Jr., Charles G. Budner, and Victor C. Norquist, Kansas City, Mo., assignors, by direct and mesne assignments, of one-half to Mid-Continent Investment Company, Kansas City, Mo., a corporation of Missouri, and one-half to Butler Manufacturing Company, Kansas City, Mo., a corporation of Missouri

Application June 9, 1932, Serial No. 616,258

3 Claims. (Cl. 110—101)

Our invention relates to an improvement in automatic coal stokers and more particularly to a means for preventing the escape of volatiles, gases, smoke and the like from the combustion pot of the stoker out through the coal duct and coal hopper. This tendency for the gases to escape in this manner is commonly termed "back smoking".

Back smoking is due to the fact that, in automatic stokers a blower is used to support the combustion in the combustion pot in which the coal burns from the top downwardly or in what is commonly termed an underfeed stoker. Frequently the furnace fire tends to clinker and form slag at the surface. This slag cap tends to prevent the free passage of air out through the combustion space and the result is that back smoking will occur.

It has been suggested, to prevent back smoking, to place the coal duct under a slight pressure either from an independent source or from the air in the air duct. In practice, it has been found that this will not prevent back smoking due to the fact that a cyclic circulation is set up within the coal duct by the positive pressure, causing the smoke and coal dust to issue from the coal hopper. This is particularly true when the fire has become slagged or when it has dropped to near the level of the coal duct. Then, too, if the supply of fuel becomes low, the pressure will escape through the coal hopper and back smoking will occur readily.

One object of our invention is to provide a means for stopping back smoking by sucking the smoke from the coal duct before it reaches the coal hopper and thus preventing its escape under all conditions.

Further objects of our invention will appear from the following description.

In the accompanying drawings which form part of the instant specification and which are to be read in conjunction therewith and in which like reference numerals are used to indicate like parts in the various views;

Figure 1 represents a plan view of one embodiment of our invention.

Figure 2 is a sectional view taken on the line 2—2 of Figure 1.

Figure 3 is a fragmentary sectional view of a modification embodying our invention.

Figure 4 is a sectional view of a modification of the form of our invention shown in Figure 3.

Figure 5 is a sectional view of another modification of the form of our invention shown in Figure 3.

In general our invention contemplates creating a partial vacuum or suction in the coal dust by means of the air in the air duct and utilizing this suction to carry away the products of combustion which escape into the coal duct and which, if permitted to escape from the coal hopper, will cause back smoking. In its broadest scope our invention consists in causing a reduced pressure in the coal duct.

More particularly referring now to the drawings, Figure 1 shows a plan view of a conventional automatic underfeed coal stoker in which the motor 1 drives the fan which is encased in housing 2, and a transmission 3 which rotates the coal screw 4 which is situated in the bottom of the coal hopper 5. The coal duct 6 connects the coal hopper 5 and the combustion pot 7. An air duct 8 is provided either coaxial with the coal duct 6 or parallel thereto and receives air from the air blower through air passage 9. The air is supplied to the combustion pot through tuyères, as is well understood in the art. An injector nozzle 10 is fitted to the coal duct 6 by means of connection 11 as can readily be seen by reference to Figure 2. The air in the air duct 8 passing through nozzle 10 will create a partial vacuum in the connection 11 which leads to the coal duct so that any smoke present therein will be carried by the ejector out through pipe 12. Pipe 12 may be led back into the air duct, to a special tuyère in the combustion pot, into the combustion space per se, into the stack, into the ash pit, or out of doors. The salient feature is that the smoke will be carried out of the basement in which the stoker is located and thus prevent the obnoxious features of back smoking. It is obvious, of course, that the smoke of back smoking contains sulphur bearing gases, carbon monoxide, and other gases which are deleterious to the health.

In the form shown in Figure 3 air duct 8a is parallel to coal duct 6. The Venturi tube 13 is connected to the air duct 8a by branch leads 14 and 15. At the point of maximum velocity a connecting pipe 11 is fitted to the coal duct as before so that the gases will escape into the rapidly moving air through the Venturi section and be carried by branch pipe 15 into the air duct. In this modification a difference of pressure can be obtained by the design of the Venturi section and is assisted by the pressure drop in the air duct due to friction.

In the form shown in Figure 4, the arrangement is the same as that shown in Figure 3 in which a Venturi section 13 is employed. In this modification a cowling 16 is fitted over the ex-

haust end of the duct 15a leading from the Venturi tube so that the passage of the air over the cowling will create a zone of reduced pressure in its vicinity assisting in the discharge of the smoke into the air duct 8a.

In the form shown in Figure 5 we place septum 17 in the air duct 8a to provide for the reduction of pressure to assist the Venturi tube in creating a cyclic flow through the Venturi tube 13 and branch pipe 15b, thus obtaining a positive suction due to the connection 11 into the air duct 8a insuring the withdrawal of volatiles which are present in the coal duct 6 due to back smoking.

It is believed that the operation of our device will be obvious from the above description. We are enabled, by the use of a Venturi section or by an ejector to convert the potential energy of pressure into the kinetic energy of velocity and to use this energy to create a zone of reduced pressure to suck the products of back smoking out of the coal duct and discharge the same into the combustion space where they will be passed out through the stack. We are enabled to obviate the difficulties of back smoking in a positive manner which will function irrespective of the level of the fire in the combustion pot or of the amount of coal in the coal hopper. It will be seen that this eliminates the disadvantages of the method of preventing back smoking hitherto proposed, namely that of attempting to put pressure in the coal duct. Our device is simple, easy to install and positive of operation.

It will be understood that certain features and subcombinations are of utility and may be employed without reference to other features and sub-combinations. This is contemplated by and is within the scope of our claims. It is further obvious that various changes may be made in details within the scope of our claims without departing from the spirit of our invention. It is,

therefore, to be understood that our invention is not to be limited to the specific details shown and described.

It will be noted that we have shown a valve 22 in each of Figures 3, 4, and 5. This valve controls the air admitted to the Venturi section and it is possible by manipulation of the valve to control the suction in order to prevent it from becoming so great as to tend to draw smoke and flame into the coal duct. It is believed that the operation of this valve will be obvious from the drawings.

Having thus described our invention, what we claim is:

1. A coal stoker including in combination a coal hopper, a coal duct communicating therewith, means for conveying coal therewith, an air duct adapted to supply air for coal being burned, a fan for blowing air through said air duct, an ejector device having a suction leg, means for supplying air from said air duct to said ejector device as the ejecting medium, and means for placing the suction leg in communication with said coal duct, the construction being such that smoke and gas in said coal duct will be entrained in the ejecting medium, and prevented from escaping from said hopper.

2. A stoker as in claim 1 including means for controlling the air supply to said ejector device.

3. An automatic coal stoker including a coal duct, an air duct, means supplying air thereto, a smaller duct communicating at both ends with said air duct and including means causing the pressure of the air from the air duct to increase the velocity of the air in the smaller duct and a duct establishing communication between said last named means and the coal duct.
